UNITED STATES PATENT OFFICE.

LEONARD G. GRAY, OF DECATUR, ILLINOIS, ASSIGNOR TO WALRUS MANUFACTURING COMPANY, OF DECATUR, ILLINOIS, A CORPORATION OF ILLINOIS.

DESIGN FOR A REFRIGERATOR DISPLAY-CASE.

•56,556.

Specification for Design.

Patented Nov. 9, 1920.

Application filed May 1, 1918. Serial No. 231,959. Term of patent 7 years.

To all whom it may concern:

Be it known that I, LEONARD G. GRAY, a citizen of the United States, residing at Decatur, in the county of Macon and State of Illinois, have invented a new, original, and ornamental Design for a Refrigerator Display-Case, of which the following is a specification, reference being had to the accompanying drawing, forming part thereof.

The figure is an isometric perspective view of a refrigerator display case, showing my new design.

I claim:

The ornamental design for a refrigerator display case, as shown.

LEONARD G. GRAY.
